WELL PUMPING DEVICE

Charles R. Hetzler, Rock Springs, Wyo.

Application October 11, 1932. Serial No. 637,222

9 Claims. (Cl. 103—232)

This invention relates to oil-well casings, and more particularly to casings of the type by which oil is expelled from the bottom portion of a well by a pressure fluid introduced into the well.

- 5 The primary object of the invention is to provide a valve-means to control the flow of pressure fluid at a point inside the casing by an adjustable element at or above the mouth of the well, and other objects reside in details of construction and 10 novel and useful arrangements and combinations of parts, by which the first named result is attained and which add to the efficiency, practicability and commercial value of the casing.

In the accompanying drawing, in the several 15 views of which like parts are similarly designated,

Figure 1 represents a vertical sectional elevation of the invention, and

Figure 2, an enlarged sectional elevation of a 20 part of the construction, which in practise is inside the well,

Figure 3 is a transverse section on the line 3—3 of Figure 1,

Figure 4 is a similar section taken on the line 25 4—4 of Figure 1,

Figure 5 is a cross section along the line 5—5 of Figure 1,

Figure 6 is a sectional view in detail, of a slip 30 used in the construction,

Figure 7 is an elevation of the upper portion of the appliance, drawn to a reduced scale and showing its connections with the outside source of pressure fluid, and

Figure 8 is an elevation showing the connection 35 of a gas tube included in the invention, with an external source of supply.

A conduit, commonly known as the well casing, is shown at 5. At the upper end of the casing in screw-threaded connection therewith, is 40 a hollow coupling 6 having an outlet opening 7. A hole 8, opposite the opening 7, is provided for the connection of a pressure gauge 9. A gate-valve 10 controls the flow of gas to the gauge, and 45 a pipe 12 is connected with the opening 7 to convey the oil lifted from the well to a distant point of delivery.

Screwed upon the upper end of the coupling is a head 13, and inside this head is a slip-ring 14 50 rotatably supported upon the end of the coupling 6 inside the head, by ball-bearings 15. The bore of the bushing is tapered at the upper end thereof for the application of a sectional, hollow slip 16, which is interiorly serrated for frictional engagement with a tubing concentrically disposed

within the casing. The slip has handle 17 to facilitate its manipulation.

The tubing is composed of sections 18 and 19 connected by a union 20. It is the upper section that engages with the slip 16. This section is 60 made of heavier material than the other and it projects through and above the head 13 for its connection with a source of pressure, usually gas obtained from the same well or from another well. When the gas is obtained from another 65 well or another external source of supply, a connection may be provided like that shown in Figure 8 in which a valve 35 controls the flow of gas from an external source of supply, diagrammatically indicated at 36, to the tube 18, and a valve 70 37 controls the flow of liquid from the tube 18 to an outlet indicated at 38 when the operation is reversed.

The head has at its upper end a stuffing box 21, with an adjustable packing gland 22 to provide a fluid-tight passage for the section 18 of the tubing. The tubing has at its lower end, an orifice 23 through which, in the operation, a pressure fluid supplied to the tubing, may enter the casing. The orifice is tapered to provide a valve-seat which cooperates with a correspondingly formed valve 24 integral with a perforated partition 25, inside a tubing 26 placed around the other tubing in spaced relation thereto. This outer tubing surrounds the lower portion of the 85 tubing 19 and extends downwardly beyond the same.

A strainer section 27 is connected to the body-part of the tubing, at the lower end thereof, by means of a collar 28, and the before-mentioned perforated partition 25 constituting a flange of the valve 24 is clamped between the sections 26 and 27 inside the collar 28. The strainer-section is perforated and closed at its lower end, and it serves to provide a screened outlet for a pressure fluid supplied to the tubing at the upper end thereof, into the casing through which the oil is lifted to the outlet.

The outside tubing has at its upper end a cap 100 piece 29 which maintains it in coaxial relation to the inner tubing, and car-springs 30 at the outside of the outer tubing engage the inner surface of the casing to frictionally hold the tubing against rotation. The cap-piece is interiorly threaded, and a nut 31 cooperating with the screw-thread of the cap-piece is welded or otherwise secured around the inner tubing 19 inside the cap 29.

In the operation of the invention, the pressure fluid entering the tubing at the upper end 110

thereof passes the valve 24, through the orifice 23, and through the perforations of the flange 25 and through those of the end-section 27, into the casing 5 at the lower end thereof. The gas or 5 other pressure-fluid causes the oil to rise in the casing to its outlet, from where it passes through the pipe 12 to a point of delivery.

It is of paramount importance that the supply of pressure-fluid be regulated at the lower 10 end of the tubing by means at a point outside the well, and this is accomplished by rotating the inner tubing from outside the head, thereby drawing the outer tubing 26 upwardly or downwardly to vary the position of the valve seat in the orifice 15 23 relative to the valve 24, it being understood that the springs 30 hold the outer tubing against rotation, without preventing its longitudinal movement.

In order to rotate the tubing, a suitable lever-appliance is clamped upon the part thereof, exteriorly of the head 13. This appliance is not a part of the present invention and has not been shown in the drawing. In order to place the tubing in the casing to the required depth, the slip 20 16 is lifted, after which the tubing may be adjusted lengthwise. By replacing the slip inside the ring, the tube is clamped in its adjusted position.

The ball bearings 15 facilitate rotation of the tubing, it being understood that there is sufficient 30 clearance between the slip-ring 14 and the tube head 13, to permit of rotation of the ring without friction.

While, within the scope of the invention, the 35 pressure fluid may be obtained from an external source, it is preferred wherever it is possible to employ the gas rising from the well to which the tubing is applied. With this object in view, a branch pipe 32 of the pipe 12, is connected with an extension 33 of the tubing 18-19, so that the 40 gas rising from the well may pass into the tubing, and through the tubing to the bottom portion of the well, as hereinbefore described.

In the above description of the invention, it 45 has been presumed that the pressure fluid enters the well by means of the tubing 19, while the oil in the well rises thru the casing 5 and is delivered thru the outlet 7 and the pipe 12.

It will be readily apparent, however, that the 50 operation may be reversed without any change in the construction and arrangement of the elements comprised in the invention. The pressure fluid may be introduced into the well by means of the pipe 12, the opening 7 and the casing 5, and the oil forced upwardly for delivery through the 55 tubings 19 and 18.

Also in case the pressure fluid is the gas rising 60 from the well, it will pass from the section 18 of the tubing thru the extension 33 and the branch pipe 32 into the pipe 12 and thru the opening 7 into the interior of the casing 5.

While within the scope of the invention either 65 of the hereinabove described methods of operating the apparatus may be employed, it has been found preferable in many instances to use the last mentioned method in which the pressure fluid is introduced into the casing and the oil is delivered by means of the tubing.

The advantages of the invention will be readily 70 apparent to those versed in the art.

The provision of the adjustable orifice in the 75 bottom of the well, and of the means for adjusting the orifice from outside the same, eliminates the necessity of pulling the tubing from the well and in consequence, avoids the use of a

derrick or other equipment heretofore employed for that purpose.

The production of the well may be continued 80 without interruption, and in high pressure wells, high pressure on the connections of the equipment is eliminated.

The necessity of having a heating plant for the application of artificial heat to keep the moisture in the gas from freezing where the pressure is reduced at the surface of the ground is also 85 35 avoided.

In this connection, it is observed that when the gas comes from the well at high pressure and the pressure is reduced at the surface, the temperature is lowered in proportion to the degree of pressure reduction, in which case artificial heat must be applied to keep the moisture in the 90 gas from freezing.

In the present invention, however, the gas pressure is reduced at the bottom of the well 95 and the temperature is maintained, notwithstanding said reduction, so that when the oil comes to the surface, it is of a temperature sufficiently high to render application of artificial heat unnecessary.

One operator can open or close the opening at the bottom of the well in a very short time and the provision of the valve-controlled orifice makes it possible to obtain oil from wells, heretofore 100 inoperative by reason of an excessively high oil-gas ratio.

Water and other condensate which under former conditions would accumulate in the well, frequently to an extent that the well had to be blown to remove the liquid, is in the use of the 105 present invention, constantly removed through the opening in the bottom of the well, and the waste of production, expense and danger to operators in blowing the well are completely eliminated.

What I claim and desire to secure by Letters Patent is:

1. The combination with a well-casing, of a tubing in the well casing having in the bottom-portion of the casing an orifice communicating 115 with the interior of the casing, an anti-friction bearing supporting the tubing for rotation, and means for opening and closing the orifice by rotation of the tubing.

2. The combination with a well-casing, of a tubing in the well casing having in the bottom-portion of the casing an orifice communicating with the interior of the casing, a head at the 125 upper end of the casing, having a fluid-tight passage for the tubing, a suspension-element for the tubing, an anti-friction bearing supporting said element in the head, and means for opening and closing the orifice by rotation of the tubing.

3. The combination with a well-casing of a tubing in the well casing having in the bottom-portion of the casing an orifice communicating with the interior of the casing, a head at the upper end of the casing, having a fluid-tight 135 passage for the tubing, a suspension-element for the tubing including a slip-ring, and a slip frictionally connecting the tubing with the ring, a bearing supporting the slip ring in the head, and means for opening and closing the orifice by rotation of the tubing.

4. The combination with a well-casing, of a rotary tubing in the well casing having in the bottom-portion of the casing an orifice, a valve cooperative with the orifice to open and close 140 the same, a tubing outside the first-mentioned 150

- tubing, carrying the valve and providing a connection between the orifice and the interior of the casing, screw-threaded members cooperating to move the outer tubing by rotation of the inner tubing, and means for holding the outer tubing against rotary movement. 5
5. The combination with a well-casing, of a rotary tubing in the well casing having in the bottom-portion of the casing an orifice, a valve cooperative with the orifice to open and close the same, a tubing outside the first-mentioned tubing, carrying the valve and providing a connection between the orifice and the interior of the casing, screw-threaded members cooperating to move the outer tubing by rotation of the inner tubing, and means for holding the outer tubing against rotary movement by frictional engagement with the casing. 10
6. The combination with a well-casing, of a tubing in the well casing having in the bottom-portion of the casing an orifice, the tubing being mounted for rotation and for longitudinal adjustment, a valve cooperating with the orifice to open and close the same, a tubing outside the first-mentioned tubing, carrying the valve and providing a connection between the orifice and the interior of the casing, screw-threaded members cooperating to move the outer tubing by rotation of the inner tubing, and means for holding the outer tubing against rotation while permitting of its longitudinal movement with the inner tubing. 15
7. The combination with a well-casing, of a tubing in the well casing having in the bottom-portion of the casing an orifice, the tubing being mounted for rotation and for longitudinal ad-
- justment, a valve cooperating with the orifice to open and close the same, a tubing outside the first-mentioned tubing, carrying the valve and providing a connection between the orifice and the interior of the casing, screw-threaded members cooperating to move the outer tubing by rotation of the inner tubing, and a spring element on the outer tubing, engaging the casing to hold the outer tubing against rotation while permitting of its longitudinal movement with the inner tubing. 80
8. The combination with a well-casing, of a rotary tubing in the well casing having in the bottom-portion of the casing an orifice, a valve cooperative with the orifice to open and close the same, a tubing outside the first-mentioned tubing, carrying the valve and providing a connection between the orifice and the interior of the casing, a screw-threaded member on the outside tubing, a nut on the inner tubing cooperating with the threaded member to move the outer tubing by rotation of the inner tubing, and means for holding the outer tubing against rotary movement. 85
9. The combination with a well-casing having an outlet for rising liquid, of a tubing in the well casing having in the bottom portion of the casing an orifice thru which a pressure fluid, supplied to the tubing, may enter the casing to lift liquid from a well, in which the casing is inserted, to the outlet, means for the rotary support of the tubing, a connection permitting of lengthwise adjustment of the tubing relative to the supporting means, and means for opening and closing the orifice from outside the well. 90
